GAS-LAMP.

No. 875,763.

Specification of Letters Patent.

Patented Jan. 7, 1908.

Application filed April 19, 1907. Serial No. 369,154.

To all whom it may concern:

Be it known that we, RICHARD W. ZIERLEIN and WILLIAM RIECHMANN, citizens of the United States, residing at St. Louis, 5 State of Missouri, have invented certain new and useful Improvements in Gas-Lamps, of which the following is a full, clear, and exact description, reference being had to the accompanying drawings, forming a part hereof.

10 Our invention has relation to improvements in gas arc-lamps; and consists in the novel details of construction fully set forth in the specification and pointed out in the claims.

15 In the drawings, Figure 1 is a half vertical section and half elevation of our improved lamp; Fig. 2 is a horizontal section on the line 2—2 of Fig. 1; Fig. 3 is a horizontal section on the line 3—3 of Fig. 1; and Fig. 4 is a 20 horizontal section on the line 4—4 of Fig. 1.

The object of our invention is to construct a gas (or vapor-burning) lamp which shall have every appearance of the prevailing type of electric arc-lamp, the lamp employing any well known incandescent mantle as a 25 direct source of light. The high efficiency of our lamp results from the control of the air which is mixed with the gas in its passage to the burner, it being the object of our invention to preheat the air complement of the combustible mixture, so that a perfect combustion is insured, and a consequent saving 30 of gas results.

A further object is to provide special 35 means for creating an upward draft for the burner flame, such draft being formed by a rising current of heated air which thus maintains the flame at the required temperature and insures for the mantle a high degree of 40 incandescence.

The present invention likewise contemplates special details in the matter of supporting the flue or chimney, in the matter of locating the gas-valve, and on the whole offers a lamp possessing advantages which will 45 be clearly apparent from a detailed description of the invention which is as follows:

Referring to the drawings, 1, represents the top or hood of the lamp, the same being 50 provided with a basal flange 2 provided with a series of openings 3 through which the light may pass and thereby reduce the shadow cast by the lamp against the ceiling. The flange 2 is formed into a depending rim 4

which receives the upper lip of a globe 5 preferably of glass, china or equivalent material, said globe being closed at the sides and bottom, and only open at the top. The hood 1 is capped by a spider 6 provided with conveniently shaped brackets 7 to which is secured the annular draft-shield or ring 8 which projects partly above and partly below the upper edge of the top of the hood. The spider 6 is provided with a tubular boss or socket 9 through which passes the gas-pipe 10 whereby the hood is capable of adjustment along said pipe, and when once adjusted is secured thereto by the clamping screw 11. Located in the pipe 10 above the hood 1 is a valve-casing 12 provided with a 60 cock or rock-valve controlled by the lever-arms 13 preferably equipped with a hand chain 14 or pendant as well understood in the art. The lower end of the gas-pipe 10 has secured thereto a box or chamber 15 which 65 terminates in tips or nozzles 16 which allow the gas to escape in the form of jets. Immediately over the box 15 there is screwed to the pipe 10 a casting 17 having an upper annular wall and a tapering lower section as 70 shown, said casting being closed at the bottom, with the exception of the openings formed therein for the reception of the burners or burner-tubes 18 whose upper enlarged heads are covered with wire gauze 19 as 75 usual.

Adjustable along the pipe 10 is a disk or bracket 20 having terminal lobes 20' for the free passage of the screw-hooks 21, said hooks being suspended by the nuts 22 which 80 upon screwing in proper direction serve to adjust the position of the hooks, and thus carefully adjust the position of the mantles M suspended therefrom. The bases of the mantles loosely embrace the tops of the 85 burners 18. Leading from a point in the pipe 10 above the hood 1 is a tube 23 which extends in proximity to the mantles and furnishes a pilot flame to the burner as well 90 understood in the art.

The wall of the upper annular portion of the burner-casting 17 is provided with a series of studs, screws, or pins 24 disposed in the same plane, which pass freely through corresponding cut-away portions or lobes 25 95 excised from a ring or band 26 adapted to be slipped over the casting from the bottom, the ring being subsequently given a slight turn 100 105

by hand to bring the lobes 25 out of alinement with the screws 24, whereupon the latter serve to support the ring about the casting. The ring has formed integrally a series 5 of arms or brackets 27 which are provided with shoulders 28 for the support of the flue or chimney C, the top of the chimney extending to the base of the flange 2. The arms 27 extend upwardly a sufficient distance 10 to bring the plane of disposition of the shoulders 28 considerably above the upper edge of the burner-casting 17, so that air may freely pass into the chimney around the mantles. Likewise the bottom of the 15 casting 17 is spaced a suitable distance from the tips 16 so as to form a mixing space for the thorough mingling of the air and gas as they are passing upward into the burners 18.

In the operation of the lamp, after the gas 20 has been turned on by proper manipulation of the gas-valve the gas will escape through the tips or nozzles 16 into the mixing space (the open space between the tips and the base of the burner casting 17) where it is 25 joined by its complement of air and the mixture passes into the burners 18. Since the globe 5 is closed on all sides as well as at the bottom, being open only on top, the air is forced to take the path indicated by the 30 feathered arrows, that is to say, it enters the space within the globe and around the chimney through the openings 3 of the flange 2, being thus brought in proximity to the chimney C whereby it is thoroughly heated, a 35 portion of the heated air mixing with the gas in the mixing space, and another portion passing through the space between the top of the burner casting 17 and base of the chimney into the chimney around the mantles, contributing not only to the necessary 40 upward draft of the lamp, but serving at all times to maintain a current of hot air around the mantles so the latter can not be cooled. In this way the incandescent efficiency of the 45 mantles is insured, being permanently enveloped in a rising current of hot air, and being themselves traversed on the inside by a hot flame.

By making the globe 5 translucent, the 50 lamp will have an appearance similar to an ordinary electric arc-lamp. While herein specifically denominated a gas lamp, it is to be understood that it may be a vapor-burner as well.

Having described our invention what we 55 claim is

1. A gas lamp comprising a gas-pipe, a hood secured thereto, a valve in the pipe located above the hood, terminal gas nozzles 60 leading from the pipe below the hood, burners above the nozzles spaced a suitable distance therefrom to form a mixing space, a chimney or flue above the burners having its bottom spaced a suitable distance from the 65 top of the burners, and an outer globe closed

at the sides and bottom and open at the top, whereby the air fed to the mixing space and to the flue is constrained to pass around the flue through the space between the flue and globe and preheated, substantially as set 70 forth.

2. In a gas lamp, a suitable burner, a flue or chimney mounted above the burner and extending to a point opposite the base of the flame, a globe closed at the sides and bottom 75 and open at the top and enveloping the flue and burner, and constraining the air to pass into the space between the flue and globe whereby the same is heated before supplying the burner, and a gas-nozzle spaced a suitable distance below the burner and discharging thereinto, the air within the globe mixing with the gas thus discharged, substantially as set forth.

3. A gas lamp having a bottom burner 85 casting or casing, gas-discharge nozzles located below the same and spaced a suitable distance therefrom, a flue mounted above the casting and having its bottom spaced a suitable distance above the top of the casting 90 and in substantial contiguity with the base of the burner-flame and an enveloping globe for constraining the passage of the air to a path around the outside of the flue whereby the air is heated, a part of the air passing upward 95 into the flue, and a part mixing with the gas jets escaping from the nozzles into the space beneath the burners of the burner-casting, substantially as set forth.

4. A lamp comprising a gas-supply pipe, a 100 hood mounted thereon, a gas-valve in the pipe above the hood, a pendant or chain for manipulating the valve, a hollow chamber at the lower end of the gas-supply pipe, nozzles terminating the chamber, a casting secured 105 to the pipe a suitable distance above the chamber and provided with open ended burners superposed over the nozzles, means on the casting for supporting a flue, the base of the latter being removed a suitable distance above the top of the casting, and a globe secured to the base of the hood and enveloping the flue, burner casting and terminal chamber of the gas pipe, the globe being 110 open on top and closed at the sides and bottom, the parts operating substantially as and for the purpose set forth.

5. In a gas-lamp, a burner casting having a series of peripheral pins or projections, a ring adapted to be passed over the casting 120 and having excised lobes for the free passage of said pins, a flue, and flue-supporting arms or brackets on the ring, adapted to elevate the bottom of the flue a suitable distance above the upper edge of the casting, the pins 125 serving to support the ring upon a turn of the latter sufficient to bring the excised lobes out of alinement with the pins, substantially as set forth.

6. In a gas lamp, a bottom burner-casting, 130

means for supporting the casting; a flue superposed thereover and spaced a suitable distance therefrom, means for supporting the flue, a mixing space below the casting, means 5 for supplying gas to said mixing space, and an enveloping globe open at the top and closed at the sides and bottom for directing the air around the flue whereby the same is heated, a portion of the heated air entering 10 the flue through the space between the bottom thereof and the top of the casting, and a

portion mixing with the escaping gas entering the mixing space and burners, substantially as set forth.

In testimony whereof we affix our signatures, in presence of two witnesses.
